(57) **CLAIM**

The ornamental design for a LP gas bottle with integral transport mechanism, as shown and described.

DESCRIPTION

FIG. 1 is a front perspective view of a LP gas bottle with integral transport mechanism showing our new design; FIG. 2 is a front view thereof;

FIG. 3 is a left side view thereof, wherein the right side view is a mirror image;

FIG. 4 is a rear view thereof;

FIG. 5 is a top view thereof;

FIG. 6 is a bottom view thereof; and,

FIG. 7 is a front perspective view of FIG. 1 shown with the handle in an alternate position.

The broken lines shown in the drawing disclosure are for illustrative purposes only and form no part of the claimed design.
